SAMUEL I. HASKELL, OF NEW YORK, N. Y., ASSIGNOR TO THE FRAENKELL & HASKELL ART COMPANY, A CORPORATION OF NEW YORK.

MOLD.

1,114,758.

Specification of Letters Patent. Patented Oct. 27, 1914.

Application filed October 31, 1913. Serial No. 798,471.

To all whom it may concern:

Be it known that I, SAMUEL I. HASKELL, a subject of the Czar of Russia, and a resident of New York, county and State of New York, have invented a certain new and useful Improvement in Molds, of which the following is a full, clear, and exact specification.

This invention relates more particularly to a class of devices adapted to be used for making doll heads.

My invention has for its object primarily to provide a mold designed to be employed for making articles of plastic material, especially doll heads, which are formed with a hollow interior whereby the article may be light in weight as well as saving a great consumption of material, and wherein is provided a shell, or die composed of two mating members, the opposed surfaces of which being cut-out to provide the die with a hollow interior to conform to the configuration of the article to be molded.

Another object of the invention is to provide a collapsible core which consists of a supporting post and a plurality of segments which serve to form the hollow-interior of the article; and still another object of the invention is to provide on one of the corresponding ends of each segment an integral gripping element, or hook which is seated in recesses in one end of the core-rod for detachably holding the segments thereo.

A further object of the invention is to provide a cap which is removably disposed over the opposite end of the core-rod and over the opposite ends of the segments when assembled; and still a further object of the invention is to provide a mold of simple and durable construction, and which is susceptible of being made in various sizes and shapes.

A practical embodiment of the invention is represented in the accompanying drawing forming a part of this specification in which similar characters of reference indicate corresponding parts in all the views, the said invention being more fully described hereinafter and then pointed out in the claims at the end of the description.

In the drawing, Figure 1 is a sectional view, partly in detail, through one form of mold embodying my invention. Fig. 2 is a sectional view partly in detail, taken longitudinally through the collapsible core

when the parts thereof are assembled. Fig. 3 is an end view of the collapsible core when assembled. Fig. 4 is a view showing in detail one-half the number of segments used in the core, and Fig. 5 is an enlarged view looking at the recessed end of the supporting post of the collapsible core.

The mold has a shell, or die 10 which may be of any suitable shape and size, and said die is composed of two mating members, or sections 11 and 12. The opposed surfaces of the mating members 11 and 12 are cut-out to provide a hollow interior 13 to conform to the configuration of the article to be molded, for instance a doll head as illustrated in the drawing. One end of each of the mating members 11 and 12 is also cut-out, to provide through the end of the die an opening 14 which communicates with the hollow interior 13 when the mating members are assembled, and through said mating members are transverse passages 15 and 15^a which communicate with the opening 14.

Serving to be employed in conjunction with the die 10 for molding an article of plastic material, and which may be formed with a hollow interior, I provide a collapsible core, as 16. The collapsible core 16 has a supporting post 17 formed with a circular tapered body portion 18, and extending from one end of said body portion is an elongated square extension 19 which is also tapered toward its free end. Projecting from the central part of the free end of the extension 19 of the supporting post is a substantially square short stem 20 which is considerably smaller in dimension than the extension of the post. In opposite parts of the free end of the extension 19, and around the stem 20 are two recesses 21 and 22 which are separated by partitions 23 and 24 extending from the stem to the marginal edge of the free end thereof, and upon the other end of the body portion 18 is formed a handle 25.

Arranged around the supporting post 17, and detachably held thereto, are a number of separate segments, as 26, 26^a, 27, 27^a, 28, 28^a, 29, 29^a, 30, 30^a. The segments 26, 27, 28, 29, 30, correspond in respective formations to the segments 26^a, 27^a, 28^a, 29^a, 30^a, and all of the segments are shaped so that when assembled on the post 17 they will approximately conform with the shape of the interior of the die 10, but the segments are made

of sizes whereby the core is smaller than the interior of the die. An article having a wall of even thickness may thereby be produced by the use of this form of mold, and a great saving may also be made in the consumption of material. The segments 26 and 26^a have enlarged body portions 31 with flat side faces, as 32 and 33. The segments 27 and 27^a have enlarged irregular triangular body portions 34 with one flat face 35 so as to abut against the faces 32 and 33 of the body portion of the segments 26, and each of the said segments 27 and 27^a have an irregular curved face, as 36. The segments 28 and 28^a have enlarged body portions 37 with irregular side faces, as 38 and 39, the faces 38 of which abut against the faces 36 of the segment 27 and 27^a, respectively. The segments 29 and 29^a have body portions 40 formed with irregular side faces, as 41 and 42, the side faces 41 of which are in contact with the faces 39 of the segments 28 and 28^a, respectively, and the segments 30 and 30^a have enlarged irregular triangular body portions 43 each having a straight face 44 which is in contact with the side faces 32 and 33 of the segment 26^a, and each of said segments 30 and 30^a also have an irregular face, as 45, one of which is in contact with the irregular face 42 of each of the segments 29 and 29^a. When the segments are assembled in this manner around the supporting post 17 the collapsible core proper is then formed, and by making the exposed faces of the segments of suitable shapes the contour of the core will conform to the shape of the interior of the die.

For the purpose of detachably holding the segments 26, 26^a, 27, 27^a, 28, 28^a, 29, 29^a, 30, 30^a to the supporting post 17, upon one of the corresponding ends of the body portion of each segment is provided a gripping element, or hook 46. All of the hooks 46 are disposed so as to be removably seated in the recesses 21 and 22 of the stem 20 of the extension 19 of the supporting post, and extending from the other end of the body portion of each of said segments is a neck 47 provided with a wedge-shaped part 48 upon its free end portion. The wedge-shaped parts 48 are formed so that when the segments are assembled upon the supporting post 17 a circular tapered head as shown at 49 in Fig. 1, will be provided so as to be disposed in the opening 14 of the die, and said head is of less diameter than the opening.

In order to retain the head 49 of the segments against movement when arranged upon the supporting post 17, I provide a removable collar, or cap, as 50. The cap 50 has an opening 51 centrally therethrough which communicates with the interior of the cap, and projecting from diametrically opposite parts of the exterior periphery of the cap are two lugs 52 and 53. When the seg-

ments and the supporting post 17 are assembled the handle 25 is disposed through the opening 51 of the cap, and the cap is then guided to encircle the head 49 of the segments. After sufficient quantity of the plastic material for making the article to be molded is placed in one or both of the mating members of the die 10 the assembled core is properly positioned between the members so that the lugs 52 and 53 will be inserted in the passages 15 and 15^a of the mating members. As is incident to the methods employed in the manufacture of this class of articles, the mold is subsequently placed under suitable pressure, and when the article is molded the mating members of the die are removed. The cap 50 is removed from the core, and the supporting post 17 is withdrawn from between the segments. The segments will then collapse interiorly of the head, and may be readily removed from the article through an open part thereof.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope of the appended claims.

Having thus described my invention, I claim as new and desire to secure by Letters Patent:—

100

1. In a mold of the character described, the combination with a die composed of two mating members, each having the opposed surface thereof cut-out to provide a hollow interior to conform in shape to the article to be molded, and each of said members having a corresponding end cut-out to form an opening through the die in communication with its interior when the mating members are assembled, of a supporting post having a handle on one of its ends, and having a recess in its opposite end, a plurality of segments detachably arranged around the supporting post, said segments being formed so as to collapse when the supporting post is withdrawn from between the segments, and said segments being made of shapes whereby the periphery of all the segments when assembled will be of less diameter than the interior of the die and will conform with the shape of the interior of said die, a plurality of gripping elements, one formed on one of the corresponding ends of each segment, said gripping elements being removably inserted in the recess of the supporting post, and a cap detachably disposed over the handle portion of the supporting post, said cap encircling the segments at the ends thereof of which are opposite to the gripping elements, and means provided upon the cap for 130

detachably holding the cap to the mating members of the die when the parts of the mold are assembled.

2. In a mold of the character described, the combination with a die composed of two mating members, each having the opposed surface thereof cut-out to provide a hollow interior to conform in shape to the article to be molded, and each of said members having a corresponding end cut-out to form an opening through the die in communication with its interior when the mating members are assembled, and each of said mating members also having a transverse passage which communicates with said opening of the die, of a supporting post having a handle on one of its ends, and having a recess in its opposite end, a plurality of segments detachably arranged around the supporting post, said segments being formed so as to collapse when the supporting post is withdrawn from between the segments, and said segments being made of shapes whereby the periphery of all the segments when assembled will be of less diameter than the interior of the die and will conform with the shape of the interior of said die, a plurality of hooks, one formed on one of the corresponding ends of each segment, said hooks being removably inserted in the recess of the supporting post, and a cap detachably disposed over the handle portion of the supporting post, said cap encircling the segments at the ends thereof which are opposite to the hooks, and two lugs projecting from the cap and each being inserted in one of the passages of the mating members of the die for detachably holding the cap to the mating members when the parts of the mold are assembled.

3. In a mold of the character described, the combination with a die composed of two mating members, each having the opposed surface thereof cut-out to provide a hollow interior to conform in shape to the article to be molded, and each of said members having a corresponding end cut-out to form an opening through the die in combination with its interior when the mating members are assembled, of a tapered supporting post having a handle on one of its ends, and having a recess in its opposite end, a stem extending from the recessed end of the tapered post, a plurality of segments detachably arranged around the supporting post, said segments being formed so as to collapse when the supporting post is withdrawn from between the segments, and said segments being made of shapes whereby the periphery of all the segments when assembled will be of less diameter than the interior of the die, a plurality of hooks, one formed on one of the corresponding ends of each segment, said hooks being removably inserted in the recess of the supporting post, and a cap detachably disposed over the handle portion of the sup-

porting post, said cap encircling the segments at the ends thereof which are opposite to the hooks, and means provided upon the cap for detachably holding the cap to the mating members of the die when the parts of the mold are assembled. 70

4. In a mold of the character described, the combination with a die composed of two mating members, each having the opposed surface thereof cut-out to provide a hollow interior to conform in shape to the article to be molded, and each of said members having a corresponding end cut-out to form an opening through the die in communication with its interior when the mating members are assembled, and a plurality of segments arranged circumferentially within the interior of the mating members, said segments being formed to provide a passage centrally therebetween so as to be adapted to collapse interiorly of the die, and said segments being made of shapes whereby the periphery of all the segments when assembled will be of less diameter than the interior of the die, of a supporting post removably disposed through the opening of the die and removably disposed in the passage between the segments, said post having a handle on one of its ends, and having a recess in its opposite end, a plurality of gripping elements, one formed on one of the corresponding ends of each segment, said gripping elements being removably inserted in the recess of the supporting post, and a cap detachably disposed over the handle portion of the supporting post, said cap encircling the segments at the ends thereof which are opposite to the gripping elements, and means provided upon the cap for detachably holding the cap to the mating members of the die when the parts of the mold are assembled. 105

5. In a mold of the character described, the combination with a die composed of two mating members, each having the opposed surface thereof cut-out to provide a hollow interior to conform in shape to the article to be molded, and each of said members having a corresponding end cut-out to form an opening through the die in communication with its interior when the mating members are assembled, and a plurality of segments arranged circumferentially within the interior of the mating members, said segments being formed to provide a passage centrally therebetween so as to be adapted to collapse interiorly of the die, and said segments being made of shapes whereby the periphery of all the segments when assembled will be of less diameter than the interior of the die, of a supporting post removably disposed through the opening of the die and removably disposed in the passage between the segments, said post having a handle on one of its ends, and having a re- 110 115 120 125 130

4

cess in its opposite end, a plurality of hooks, one formed on one of the corresponding ends of each segment, said hooks being removably inserted in the recess of the supporting post, and a cap detachably disposed over the handle portion of the supporting post, said cap encircling the segments at the ends thereof which are opposite to the gripping elements, and means provided upon the cap for detachably holding the cap to the mating members of the die when the parts of the mold are assembled.

6. In a mold of the character described, the combination with a die composed of 15 two mating members, each having the opposed surface thereof cut-out to provide a hollow interior to conform in shape to the article to be molded, and each of said members having a corresponding end cut-out to 20 form an opening through the die in communication with its interior when the mating members are assembled, and each of said mating members having a transverse passage therethrough, and a plurality of segments arranged circumferentially within the 25 interior of the mating members, said segments being formed to provide a passage centrally therebetween so as to be adapted

to collapse interiorly and said segments being made of shapes whereby the periphery 30 of all the segments when assembled will be of less diameter than the interior of the die, of a tapered supporting post removably disposed in the passage between the segments, 35 said post having a handle on one of its ends, and having a recess in its opposite end, a plurality of hooks, one formed on one of the corresponding ends of each segment, said hooks being removably inserted in the recess of the supporting post, and a cap detachably disposed over the handle portion of the supporting post, said cap encircling the segments at the ends thereof which are opposite to the gripping elements, and two 40 lugs provided upon the cap, and removably disposed in the passages of the mating members for detachably holding the cap to the mating members of the die when the parts of the mold are assembled.

This specification signed and witnessed 50 this thirtieth day of October A. D. 1913.
